UNITED STATES PATENT OFFICE.

CHRISTIAN W. MEINECKE, OF JERSEY CITY, AND DANIEL HOGAN, OF HOBOKEN,
NEW JERSEY.

DESIGN FOR A BED-PAN.

No. 39,236.

Specification for Design. Patented March 31, 1908.

Application filed January 10, 1908. Serial No. 410,273. Term of patent 14 years.

To all whom it may concern:

Be it known that we, CHRISTIAN W. MEINECKE and DANIEL HOGAN, both citizens of the United States, and residents, respectively, of Jersey City and Hoboken, in the county of Hudson and State of New Jersey, have jointly invented a new, original, and ornamental Design for a Bed-Pan, of which the following is a specification.

Reference is to be had to the accompanying drawing in which

Figure 1 is a plan view of a bed pan show-

ing our new design; Fig. 2 is a side elevation thereof, and Fig. 3 is an end view of said bed pan.

We claim:

The ornamental design for a bed pan as shown:

CHRISTIAN W. MEINECKE.
DANIEL HOGAN.
